ADJUSTABLE MUTE

Frederick Gosparlin, Glendale, Calif.

Application July 8, 1946, Serial No. 681,840

2 Claims. (Cl. 84—310)

1

This invention relates to mutes for a violin.

An object of this invention is to provide a mute for a violin, viola, cello, bass, or other high bridged musical stringed instruments, to soften, beautify, and otherwise control the tone of this type of instrument.

Another object of this invention is to provide an adjustable mute of this kind whereby the bridge of the instrument is free to vibrate between tone controllers which are adjustably supported on either side of the bridge by gripping means which engage the base of the bridge below the waistline thereof, thus permitting the vibratory tones to be adjustably selected.

Another object of this invention is to provide an adjustable mute of the kind to be hereinafter described, which eliminates the wolf tones which usually are developed by other mutes of this type by virtue of the fact that the weight of the mute does not rest on the upper end of the bridge which is vibrated by the strings, but rather is supported by the base of the bridge which is not vibrated and therefore, does not effect the tone.

Yet another object of this invention is to provide an adjustable mute of this kind wherein the upper part of the bridge, above the waistline, is free to vibrate between tone controllers which are vertically adjustable on the bridge, whereby a range of tone control is readily selectable by the artist to his particular choice at any and all times, thereby providing for the maximum amount of pleasure and personal satisfaction for the artist.

A still further object of this invention is to provide a precision adjustable tone control violin family mute of the kind described, to soften, beautify, and control the tone of the violin at the fancy of the artist.

A still further object of this invention is to provide a mute of this kind which may be made of wood or metal, or any other suitable material, at a reasonable cost, whereby this controlled tone mute may be readily available to all artists who may desire the precision tone control which this mute makes available.

With the above and other objects in view, my invention consists in the arrangement, combination and details of construction disclosed in the drawings and specifications, and then more particularly pointed out in the appended claims.

In the drawings,

Figure 1 is a front elevation of this mute on a violin bridge, the violin being shown in a fragmentary section,

2

Figure 2 is a side elevation of the mute and bridge taken on the line 2—2 of Figure 1.

Figure 3 is a vertical section, taken on the line 3—3 of Figure 1.

Referring to the drawings, the numeral 10 designates generally the upper surface of a violin or other similar high bridged stringed musical instrument. The bridge 11 is supported on the violin 10 in the usual manner between the strings and the upper wall of the violin. The numeral 10 designates generally the lower end or base of the bridge 11 and the numeral 14 designates the upper end, above the waistline 15, which is vibrated in accordance with the vibration of the strings, not shown.

Artists frequently desire to use mutes on violins to soften the tones and heretofore the mutes have been such as to engage snugly over the strings onto the upper end of the bridge in such a manner, as to permit the strings to vibrate yet dampening the vibration of the bridge by the weight of the mute. This weight of the mute on the vibrating bridge results in certain undesirable wolfish tones. This mute of my invention is designed to soften the tone of the instrument without the heretofore consequent wolf tones, since the weight of the mute is carried by the base 12 of the bridge permitting the vibration of the upper end 14 of the bridge 11.

This mute 16 constructed according to an embodiment of my invention is formed with an upper body section 17 which may be made of metal, wood or other suitable material. The body 17 is formed of a flat piece of selected material having an arcuately contoured rounded upper edge 18, and a pair of opposed downwardly extending tone controlling or adjusting arms 19 depending from each end.

An annular soft resilient pad 20 is fixed to the lower inside end of each arm 19 and is adapted to engage the sides of the upper end of the bridge 11 when the bridge is vibrated for controlling the tone of the instrument. The opposed arms 19 are longitudinally spaced apart a slight distance together with the pads 20 so that the bridge is quite gently engaged by the pads 20, there being no vertical force as the weight of the mute acting on the upper end 14 of the bridge.

For supporting the mute 16 on the bridge 11 in the desired position there are provided a pair of oppositely disposed downwardly extending supporting arms or stabilizers 21. The arms 21 are spaced inwardly of the tone controlling arms 19 and extend downwardly much farther than the arms 19. The arms 20 are gently bowed out-

wardly as seen in Figure 2, whereby they are completely free of the upper end 14 of the bridge and engage the bridge 11 on opposite sides of the lower section 12. The bridge engaging ends 22 of the arms 21 are curved on their upper and lower edges whereby the mute 16 may easily be slid on and off of the bridge 11 without injuring the surface thereof. The ends 22 tightly engage the bridge 11 by virtue of the resiliency of the bowed arms 21 for securely supporting the mute 16 on the bridge.

For adjusting and controlling the tone of the muted instrument, there is provided a control or set screw 24 which is threadably engaged vertically through the longitudinal and medial center of the body 17. The screw 24 extends downwardly from the body 17 between the upper end of the arms 21 and the lower end of the screw 24 is rounded for smoothly engaging the upper edge of the bridge 11. Clockwise rotation of the control screw 24 effects vertically raising the mute 16 on the bridge 11 for lightening the tones. A knurled knob 25 on the upper end of the control screw 24 above the bridge 11 is provided for finger tip control by the artist.

In the use and operation of this wolfless mute 16 the set screw 24 is first threaded to its outermost upper extremity whereby the mute 16 may be engaged on the bridge 11 as far down as possible with the lower edge of the body 17 substantially engaging the upper edge of the bridge. This position results in wolf tones similar to conventional mutes as the weight of the mute 16 is in engagement with the upper end 14 of the bridge 11. The artist now adjusts the tone to that which he finds most desirable by turning the control screw clockwise to raise the mute 16. The knob 25 and screw 24 are rotated until the desired tone is found, which tone will still be wolfish as the weight of the mute still engages the upper end of the bridge 11. To remove the wolf tones, the screw 24 is then rotated counter-clockwise on half a turn sufficiently to disengage the screw 24 from the bridge 11 at which time the mute 16 is totally supported from the lower end of the bridge 11, below the waistline 15 by the supporting arms 21 and the upper end 14 of the bridge is vibrated freely of the weight of the mute between the tone control arms 19 and pads 20.

I do not mean to confine myself to the exact

details of construction herein disclosed, but claim all variations falling within the purview of the appended claims.

What I claim is:

- 5 1. An adjustable mute for a high-bridged musical instrument comprising, an upper body section, an oppositely-disposed pair of tone-controlling arms depending downwardly from each end portion of said body section for engaging the bridge 11 at points above the waistline thereof, a pair of oppositely-disposed supporting arms depending downwardly from said body section intermediate said pair of tone-controlling arms and adapted to support the mute at points below the waistline 15 of the bridge, resilient pads on the adjacent surfaces of each of the pairs of tone-controlling arms which are engageable with the bridge, and means adjustably carried by said body section adapted to be moved towards and away from the upper side of the bridge.
- 10 2. An adjustable mute for a high-bridged musical instrument comprising, an upper body section, a pair of oppositely disposed supporting arms depending downwardly from the central portion 15 of said body section and adapted to slidably engage the bridge, a pair of spaced tone-controlling arms depending downwardly from opposite ends of said body section for engaging the bridge, the first named pair of arms being of such length as to normally engage the bridge below the waistline thereof and the last named pairs of arms being of such length as to normally engage the bridge above the waistline thereof, and means associated with said body section approximately midway between the opposite ends thereof movable into and out of bearing engagement with the upper surface of the bridge, all adapted and arranged whereby the mute may be adjusted vertically with respect to the vertical axis of the bridge and thereby the relative vibrations of the bridge above and below the waistline thereof may be controlled.
- 15 3. An adjustable mute for a high-bridged musical instrument comprising, an upper body section, a pair of oppositely disposed supporting arms depending downwardly from the central portion 20 of said body section and adapted to slidably engage the bridge, a pair of spaced tone-controlling arms depending downwardly from opposite ends of said body section for engaging the bridge, the first named pair of arms being of such length as to normally engage the bridge below the waistline thereof and the last named pairs of arms being of such length as to normally engage the bridge above the waistline thereof, and means associated with said body section approximately midway between the opposite ends thereof movable into and out of bearing engagement with the upper surface of the bridge, all adapted and arranged whereby the mute may be adjusted vertically with respect to the vertical axis of the bridge and thereby the relative vibrations of the bridge above and below the waistline thereof may be controlled.
- 20 4. An adjustable mute for a high-bridged musical instrument comprising, an upper body section, a pair of oppositely disposed supporting arms depending downwardly from the central portion 25 of said body section and adapted to slidably engage the bridge, a pair of spaced tone-controlling arms depending downwardly from opposite ends of said body section for engaging the bridge, the first named pair of arms being of such length as to normally engage the bridge below the waistline thereof and the last named pairs of arms being of such length as to normally engage the bridge above the waistline thereof, and means associated with said body section approximately midway between the opposite ends thereof movable into and out of bearing engagement with the upper surface of the bridge, all adapted and arranged whereby the mute may be adjusted vertically with respect to the vertical axis of the bridge and thereby the relative vibrations of the bridge above and below the waistline thereof may be controlled.
- 25 5. An adjustable mute for a high-bridged musical instrument comprising, an upper body section, a pair of oppositely disposed supporting arms depending downwardly from the central portion 30 of said body section and adapted to slidably engage the bridge, a pair of spaced tone-controlling arms depending downwardly from opposite ends of said body section for engaging the bridge, the first named pair of arms being of such length as to normally engage the bridge below the waistline thereof and the last named pairs of arms being of such length as to normally engage the bridge above the waistline thereof, and means associated with said body section approximately midway between the opposite ends thereof movable into and out of bearing engagement with the upper surface of the bridge, all adapted and arranged whereby the mute may be adjusted vertically with respect to the vertical axis of the bridge and thereby the relative vibrations of the bridge above and below the waistline thereof may be controlled.
- 30 6. An adjustable mute for a high-bridged musical instrument comprising, an upper body section, a pair of oppositely disposed supporting arms depending downwardly from the central portion 35 of said body section and adapted to slidably engage the bridge, a pair of spaced tone-controlling arms depending downwardly from opposite ends of said body section for engaging the bridge, the first named pair of arms being of such length as to normally engage the bridge below the waistline thereof and the last named pairs of arms being of such length as to normally engage the bridge above the waistline thereof, and means associated with said body section approximately midway between the opposite ends thereof movable into and out of bearing engagement with the upper surface of the bridge, all adapted and arranged whereby the mute may be adjusted vertically with respect to the vertical axis of the bridge and thereby the relative vibrations of the bridge above and below the waistline thereof may be controlled.
- 35 7. An adjustable mute for a high-bridged musical instrument comprising, an upper body section, a pair of oppositely disposed supporting arms depending downwardly from the central portion 40 of said body section and adapted to slidably engage the bridge, a pair of spaced tone-controlling arms depending downwardly from opposite ends of said body section for engaging the bridge, the first named pair of arms being of such length as to normally engage the bridge below the waistline thereof and the last named pairs of arms being of such length as to normally engage the bridge above the waistline thereof, and means associated with said body section approximately midway between the opposite ends thereof movable into and out of bearing engagement with the upper surface of the bridge, all adapted and arranged whereby the mute may be adjusted vertically with respect to the vertical axis of the bridge and thereby the relative vibrations of the bridge above and below the waistline thereof may be controlled.
- 40 8. An adjustable mute for a high-bridged musical instrument comprising, an upper body section, a pair of oppositely disposed supporting arms depending downwardly from the central portion 45 of said body section and adapted to slidably engage the bridge, a pair of spaced tone-controlling arms depending downwardly from opposite ends of said body section for engaging the bridge, the first named pair of arms being of such length as to normally engage the bridge below the waistline thereof and the last named pairs of arms being of such length as to normally engage the bridge above the waistline thereof, and means associated with said body section approximately midway between the opposite ends thereof movable into and out of bearing engagement with the upper surface of the bridge, all adapted and arranged whereby the mute may be adjusted vertically with respect to the vertical axis of the bridge and thereby the relative vibrations of the bridge above and below the waistline thereof may be controlled.
- 45 9. An adjustable mute for a high-bridged musical instrument comprising, an upper body section, a pair of oppositely disposed supporting arms depending downwardly from the central portion 50 of said body section and adapted to slidably engage the bridge, a pair of spaced tone-controlling arms depending downwardly from opposite ends of said body section for engaging the bridge, the first named pair of arms being of such length as to normally engage the bridge below the waistline thereof and the last named pairs of arms being of such length as to normally engage the bridge above the waistline thereof, and means associated with said body section approximately midway between the opposite ends thereof movable into and out of bearing engagement with the upper surface of the bridge, all adapted and arranged whereby the mute may be adjusted vertically with respect to the vertical axis of the bridge and thereby the relative vibrations of the bridge above and below the waistline thereof may be controlled.
